UNITED STATES PATENT OFFICE.

JOHN B. WALKER, OF BIRMINGHAM, ALABAMA.

MOLDING APPARATUS.

1,262,720.

Specification of Letters Patent. Patented Apr. 16, 1918.

Application filed October 10, 1917. Serial No. 195,850.

To all whom it may concern:

Be it known that I, JOHN B. WALKER, a citizen of the United States of America, residing at Birmingham, in the county of 5 Jefferson and State of Alabama, have invented certain new and useful Improvements in Molding Apparatus, of which the following is a specification.

My invention relates to the art of making 10 sand molds and cores for use in casting ingot molds, large pipe and like heavy tubular bodies, and consists in the novel mechanisms hereinafter more fully explained, which have for their object the 15 simultaneous formation of both core and mold or cheek on a jarring table, and the adaptation of parts to be mechanically handled throughout.

My invention is especially (but not exclusively) adapted to form, in one operation by the use of a jarring table or jolt machine, both the sand core and the cheek or mold thus enabling me to greatly simplify and cheapen the cost of mold production 25 and at the same time to produce a standard of uniformity in the packing of both cheek and core that cannot reliably be obtained otherwise.

A further object of my invention is to 30 design the several parts of the apparatus employed in carrying my process into effect so that a crane or hoist mechanism can be employed in the handling of parts during the several stripping and assembling operations 35 incident to the sand packing or ramming, the casting, and the shaking out operations.

I have found that by thus reducing to a minimum the number of operations and 40 eliminating as far as possible any manual handling of parts of the apparatus, I am enabled to bring the cost of production down to a minimum, and to conduct the whole operation for the production of these 45 heavy castings with a facility and speed fully equal to the best practice now obtaining for small castings.

A further object of my invention is to 50 provide means whereby the pattern may be held against displacement when the cheek is stripped vertically therefrom and in the simplification of the mechanism for expanding the arbor thus described in my Letters Patent No. 1,151,229. This application

forms a continuation in part of the application filed by me on March 12th, 1917, and resulting in the issue to me of Letters Patent No. 1,242,747, dated October 9th, 1917.

As illustrative of the apparatus now regarded as the preferred embodiment of my invention, reference is made to the accompanying drawings, in which:

Figure 1 is a vertical sectional view taken with one-half of the flask removed and one of the pattern lugs withdrawn, the section being taken on the line 1—1 of Fig. 4.

Fig. 2 is an elevation of the flask broken away to show the split edge of the pattern, all parts being in position for receiving the sand.

Fig. 3 is a detail view of the means for limiting the expanding movement of the pattern.

Fig. 4 is a top plan view of Fig. 1 with both pattern lugs in place.

Fig. 5 is a detail perspective view of the top of the arbor showing the top wedge plate with its fastening pin and wedge key.

Fig. 6 is a detail view showing the apparatus for holding down the pattern and the manner of applying the crane hooks to lift the pattern after the hold-down means are removed.

Fig. 7 is a detail view in vertical section through the top of the collapsible core arbor showing the mechanism controlling all four arbor staves.

Similar reference numerals refer to similar parts throughout the drawings.

A jolt machine or jarring table 1 is formally illustrated and has mounted thereon a removable stool drag 2 to which the center column 3 of a collapsible core arbor is secured by a wedge key 4. The arbor is formed by four collapsible staves 5, two only of which carry at their upper ends internal socket bearings 5^a in which the pawls 5^b are mounted free to rock and disposed upwardly so as to engage wide side faces of the column 3 of the arbor at a point above the top 100 of the staves. The staves have lapping corner joints as described in my Letters Patent No. 1,221,116, and only the two opposite staves carrying the inner flanges are provided with the sockets 5^a and the pawls 5^b. The staves are expanded by the action of a plate 6 and wedge key 6^a on the column 95 which plate is movable downwardly by the

action of the wedge to engage the pawls and press them downwardly so as to force the pawl carrying staves outwardly until arrested by the engagement of lugs 6^b on the 5 staves with stop lugs 3^b on the column. The engagement between the underlying flanges of these staves and the overlying flanges of the other pair of staves is such as to move all of the staves outwardly together until all 10 engage their respective stop lugs 3^b and are held in rigid relationship with the column. The staves at their lower ends are mounted to rock in the sockets 2^b on the stool drag. The staves are operated to expand or contract 15 the arbor, all as more fully described in my said Letters Patent No. 1,221,116. The stool is recessed in its upper face at 7 to form the drag portion of the mold. A stripping plate 8 is mounted on the stool drag and clamped in position to receive and 20 center the lower end of the pattern which is shown in tubular form as generally used for the manufacture of ingot molds, though its shape can be modified for the manufacture 25 of other articles. The pattern is substantially rectangular in cross section and is split diagonally through its corners in a vertical plane preferably into two half sections 9 and 10, each section carrying about its top 30 edge a protecting plate 11 with upturned perforated lugs or ears 12 at its ends. These lugs or ears are arranged to overhang so that the centers of their holes when in register will lie in the plane of parting between the 35 pattern sections. Between each pair of lugs 12 I interpose a hanger plate 13 having a hole therein adapted to register with the holes in the lugs so that the bolts 14, which pivotally connect the lugs, will also hold 40 the hanger plates in position between them. The upper free ends of these plates are provided with holes 15 to receive hooks 16 of the crane or hoisting tackle. The pattern section 9 in each upper side 45 edge is provided with a countersunk seat to receive a plate 17 carrying a dowel pin 18, and in its lower portion is a countersunk seat which receives a plate 19 having a stop lug 20 with a downturned hook 21 at its 50 outer end. The side edges of the pattern section 10 have countersunk seats, the upper of which receive plates 22 having dowel pin holes 23 therein disposed to receive the dowel pins 18. The lower seats receive plates 24 55 having holes 25 into which the stop lugs 20 project with a close sliding side fit but with the bottom of the hole in position to clear the underface of the lug but to engage the downturned hook 21 at the outer end of the 60 lug. By this arrangement the lugs and the pins hold the flask sections against lateral displacement while permitting them to swing apart freely on their pivot bolts 14 until the hooks engage the plates 24, 65 thus limiting the opening or expanding

movement of the pattern. It is of importance to note that I provide the lower countersunk seats for the plates 24 with an opening 26 leading downwardly and at an incline outwardly through the face of the 70 pattern, so that the sand can escape from the lug holes 25, it being essential that these holes shall not become packed with the sand as thereby the automatically closing action of the pattern sections might be interfered 75 with.

The flask as described in my Letters Patent No. 1,221,117, is divided vertically into half sections 27 and 28, each having at its upper edge overhanging perforated lugs 29 80 which lap and each pair of which is hingedly connected by a pivot bolt 30. Each flask section carries a plurality of lifting lugs for engagement with the hoist tackle, the lugs 31 near the side edges being termed "closing" 85 lugs and the lugs 32 being termed "opening" lugs.

The upper end of the column 3 is provided with a head 33 having a hole 34 for the crane or lifting tackle and having overhanging lugs 35 under which I engage hold-down bars 36 for the pattern, these bars having their under ends notched to form depending lips 37 which engage the inner wall of the pattern and prevent the pattern moving 95 upwardly when the cheek is stripped from the stool drag and pattern. The bottom edges of the pattern are cut away to receive reinforcing metal plates 46. Clamps 45 are employed to hold the flask, stripping plate and stool together, and clamps 49 to secure the stripping plate to the flask. 100

Assuming the stool with the stripping plate, flask and core arbor assembled thereon by their respective fastenings 49, 45 and 105 4 in position on the jarring table, the pattern is seated on the stool with its bottom end left free of any rigid fastening. Sand is first shoveled between the pattern and the flask to a height of about a foot, the jarring table is then operated to give the apparatus three or four jolts which compacts this sand about the pattern so that it will form an encircling sand band which will force together and hold in that position the 110 lower or free ends of the pattern sections. Having thus preliminarily secured the pattern in position, sand is filled in on both the inside and outside of the pattern and the jolting operation proceeds until the sand 115 is packed practically to the top level of the pattern. 120

It will be observed that the pattern does not carry lugs for forming the ears or lugs on the ingot mold and my reason for leaving the exterior of the pattern free of projections will be apparent when it is considered that my purpose is to pack the sand by the jolting or jarring process. If the lugs were 125 formed on the pattern it would be practically 130

impossible to mechanically accomplish the proper packing of the sand under the lugs. In accordance with my present invention, the operator uses a shovel, the blade of which 5 is shaped so that when thrust downwardly into the packed sand around the top of the pattern, it will remove sufficient of the sand to form a seat which will receive the detached lug patterns 38 which are then set 10 in position against the pattern sections 9 and 10. To insure the lug patterns being set in the right position, they are provided with tongues 39 that fit into vertical slots 40 in the pattern and top reinforcing plate 45. 15 After seating the lug patterns, additional sand is thrown over them and rammed. When this has been accomplished, clamps 45 are knocked off and the crane is first applied, in the manner described in my Letters 20 Patent No. 1,221,117, to lift the flask and strip the cheek from the pattern and stool drag and deliver it to foundry pits for finishing. The lug patterns will be stripped off with the cheek and can readily 25 be drawn as part of the finishing operation. The crane hooks are then applied to the hanger plates 13 of the pattern and, the encircling sand band which forms part of the cheek having been removed, the bottom end 30 of the pattern is released to expand to the full extent permitted by the stop lugs 20. As the pattern is lifted to strip it from the core, it will ride freely up the core and the latter will be thus protected from collapse 35 or injury. As soon as the pattern clears the core it can be set over another core arbor and the operation repeated, it being noted that the pattern sections will swing together into closed position by gravity as soon as they 40 are free of the core.

By utilizing the method suggested of forming the sand band for contracting the pattern I save one operation required to contract and secure the pattern sections together and another operation to release them so that the pattern can expand. It will be understood however that the sand band is only the preferred means, as my invention contemplates the use of any device or means 50 which will hold the pattern contracted during the ramming operation and which will strip with the cheek. In order to facilitate the stripping of the cheek, the pattern is preferably formed with a slight taper upwardly and this taper is effective within the pattern also to facilitate its stripping from the core. Before closing the mold the clamps 49 are knocked loose and the stripping plate 8 removed, this being done after 55 the cheek has been dried.

My object is to so design the apparatus that the casting can be stripped without losing the sand coating formed by the sand of both cheek and core, thus permitting the 60 casting to anneal in the sand in which it

was cast and without requiring any additional operation or expense. It is of course apparent that castings allowed thus to anneal are superior to the other castings which are subjected to strains and stresses of a 70 rapid and unequal cooling. In carrying this part of my invention into effect it is necessary to provide means for releasing the flask sections so that they will expand, this means as shown in Fig. 2 being the clamps 75 41 which engage the side flanges 42 of the flask sections preferably by being inserted in notches 43 formed therein, such an arrangement permitting the clamp to seat vertically so that it will not tend to jar loose 80 in the jolt ramming process. A loose bolt 44 is passed freely through the lower ends of the flanges to limit their parting movement about their hinge bolts 30.

The stripping operation for the casting is 85 as follows:—The crane loops are applied to the closing lugs 31 of the flask, the wedge plate 6 is relaxed to permit the core arbor sections to contract, as shown in dotted lines Fig. 7, and the flask, cheek, casting and the 90 sand coating about the arbor are all stripped vertically from the arbor, which stripping operation is facilitated by the collapsing of the arbor staves as they rock toward each other in their socket bearings 2^b. In practice, I have no difficulty in stripping the sand core from the arbor without losing the sand except a small amount dislodged at the corner joints of the core by the collapsing 95 action of the staves. The hoisting tackle is 100 then transferred to the opening lugs 32, the clamps 41 are detached and the flask expands so that it will strip freely when lifted upwardly so as to leave the sand cheek adhering to the casting. The casting is 105 stripped at the point where it is desired to leave it during the annealing process and its sand coating is left on the casting until it is thoroughly cooled, when the sand will strip freely and easily from the casting, 110 leaving a smooth annealed casting forming an ingot mold of unusual quality and durability.

In order to secure the wedge plate 6 against removal from the arbor column 3, I 115 provide a U-shaped pin 47, which is adapted to be passed through the wedge opening at the top of the column and to have its down-turned ends inserted through suitable openings provided therefor in the wedge plate 6. 120 The wedge key 6^a is adapted to be driven in the opening 48 and to bear on the top of this pin 47, as will be seen more clearly in Fig. 7, and should the wedge key 6^a be removed for any reason, which is not necessary, this pin would still serve to prevent the wedge plate being lifted off of the arbor or becoming displaced. 125

This invention is not intended to be restricted in scope to the specific embodiment 130

shown, but contemplates such modifications as come within the spirit and scope of the claims.

Having thus described my invention, what I claim as new and desire to secure by Letters Patent, is:—

1. In combination, a flask, a drag, a tapering hollow pattern seated on the drag and split vertically into sections, means to assemble the pattern sections with their lower ends free to part, and means for holding the pattern contracted, which is adapted to be stripped therefrom vertically with the flask and cheek.
2. In a molding apparatus adapted to be rammed on a jolt machine, a flask, a core arbor, a pattern interposed between the arbor and flask, a drag, and releasable means adapted to engage and hold down the pattern on said drag while the cheek is stripped vertically therefrom.
3. In combination, a stool drag, a core arbor having a center column made fast to the said drag, a pattern seated on the drag, a flask, and hold-down means interposed between the pattern and column to hold down the pattern while the cheek is stripped vertically therefrom.
4. In combination, a stool drag, a core arbor having a center column made fast to the said drag, a pattern seated on the drag, a flask, and detachable hold-down means interposed between the pattern and column to hold the pattern while the cheek is stripped vertically therefrom.
5. In combination, a stool drag, a core arbor column made fast thereto, core arbor staves having a rocking bearing on said drag, stave expanding mechanism on the column, shoulders on the column above the staves, and pattern engaging hold-down arms adapted to engage under said shoulders, as and for the purposes described.
6. In combination, a flask formed by vertical sections hingedly connected at their upper ends, a pattern formed by vertical sections hingedly connected at their upper ends, a collapsible core arbor, and a drag to which said flask, pattern and arbor are connected.
7. In combination, a drag adapted to be mounted on a jarring table, a collapsible core arbor, means to hold the core arbor

when expanded, in rigid relationship with the drag, a pattern surrounding the core 65 arbor, and releasable means to hold the pattern against vertical movement relative to said core arbor.

8. In a molding apparatus, a pattern for ingot molds and like articles divided into 60 vertical sections movable relatively to expand or contract the pattern, a core arbor within the pattern, a flask about the pattern, and means to hold the pattern contracted during the ramming operation, said means 65 being movable to release the pattern so that it is free to expand while being stripped from the sand core formed therein.

9. In an apparatus for producing jolt rammed sand molds for hollow castings, a 70 stool drag, an arbor column made fast to the drag, an arbor formed by staves collapsible toward the arbor, means to hold the expanded arbor rigid on the drag, an expansible pattern adapted to be stripped vertically 75 from the sand core, and an expansible flask adapted, when expanded, to strip freely vertically from the sand cheek.

10. In an apparatus for producing jolt rammed sand molds for hollow castings, a 80 stool drag, an arbor column made fast to the drag, an arbor formed by staves collapsible toward the arbor, means to hold the expanded arbor rigid on the drag, an expansible pattern adapted to be stripped vertically 85 from the sand core, an expansible flask adapted, when expanded, to strip freely vertically from the sand cheek, a stripping plate detachably secured to the flask base and adapted to support the sand cheek therein, 90 and means to hold-down the pattern when the sand cheek is stripped vertically therefrom.

11. In an apparatus for producing jolt rammed sand molds for hollow castings, a 95 stool drag, an expansible flask formed by vertical sections, releasable means to hold the sections closed, a stripping plate for the sand cheek only, and means to clamp said stripping plate to the bottom of the several 100 flask sections.

In testimony whereof I affix my signature.

JOHN B. WALKER.
